UNITED STATES PATENT OFFICE.

JOHN H. BURKHOLDER, OF ASHLAND, OHIO, ASSIGNOR TO THE ELITE MANUFACTURING COMPANY, OF ASHLAND, OHIO, A CORPORATION.

LIFT-JACK.

1,238,723.

Specification of Letters Patent. Patented Aug. 28, 1917.

Application filed February 12, 1916. Serial No. 77,969.

To all whom it may concern:

Be it known that I, JOHN H. BURKHOLDER, a citizen of the United States, residing at Ashland, in the county of Ashland and State 5 of Ohio, have invented certain new and useful Improvements in Lift-Jacks, of which the following is a specification.

This invention relates to improvements in Lift Jacks, of a type employing a plurality of pawls or dogs and which in this instance are under the control of a single releasing member or unit, all substantially as shown and described and particularly pointed out in the claims.

In the accompanying drawings, Figure 1 is a vertical sectional elevation of the jack in one of the several forms shown. Fig. 2 is a sectional elevation on line 2—2, Fig. 1. Fig. 3 is a cross section looking down 20 on line 3—3, Fig. 1.

Fig. 4, Sheet 2, is a sectional elevation corresponding substantially to Fig. 1, but with the pawls and their actuating parts in a different relation. Fig. 5 is a sectional elevation of a modification of the jack particularly in the location and operation of the outer pawl, and Fig. 6 is a sectional elevation of still another modification. Figs. 7 and 8 are details of the respective pawls or 30 dogs.

The jack as thus shown has a standard S in and upon which the operating parts are mounted, and the present description applies first to Figs. 1 to 4 inclusive. The 35 rack-bar *b* is slidably mounted in the said standard, as usual, and has teeth *2* on its inner edge. The said teeth are adapted to be engaged by the pawls *4* and *5*, also referred to as inner and outer pawls, and in 40 Figs. 1 to 4 are shown as pivoted at 3 and 6 respectively on the inner end of the operating handle *h*, or the socket therefor and which constitutes a portion of the handle as understood herein. The said pivots 45 3 and 6 are equidistant from the handle pivot 7 on said standard or the swell or enlargement thereof within which the said

pawls are housed, and said pawls are adapted to act in both raising and lowering the rack-bar as will presently be seen. 50

A single pawl releasing member or device *d* is employed in this jack and located relatively beneath the said pawls and slidably mounted in the well *9* in the base of enlargement 8. The said well is barrel-shaped and said device has a head 10 with a circular guide portion depending in said well and a flat top portion with a projection *f* at its inner side and a horizontal portion *g* at its outer side, and a stem 14 projects from 60 said head 10 down through the bottom of well 9 and has a cam lever 15 pivoted on the lower end thereof. A spiral spring 16 encircles said stem between the head 10 and the bottom of said well and is adapted normally to exert an upward tension and lift or raise said device with power to throw out the pawls. Otherwise the head 10 is depressed or drawn down by the action of cam lever 15 bearing against the bottom 65 of well 9 and retiring said device *d* from action.

The pawl 4 has a toe or point 18 next behind its pivot adapted to be engaged by the projection *f* on head 10, while pawl 5 75 has a toe 20 adapted to be engaged by the flat top surface of said head, and these engagements are dependent upon the position of the operating lever *h* which has its socket portion pivoted at 7. 80

Now, having the parts associated and related as seen in Figs. 1 and 2 with the pawl raising device or member *d* raised as shown therein, the said parts are in lowering position for the rack-bar in a step-by-step, 85 or tooth-by-tooth, movement controlled by said pawls and the lever or handle *h*. However, it should have been stated that each of the pawls has a spring 25 arranged and adapted to normally press the pawl toward or into engagement with the rack-bar, and the tension of the said springs is overcome only by means of the greater 90 pressure or lift exerted by the device *d* as

the said pawls are successively released from engagement with the rack-bar by the handle or lever on which they are pivoted.

Thus, if the rack-bar is to be lowered as shown in these views, the raising of the handle lowers and releases pawl 4 and it is thrown out and back as seen in Fig. 1 by engagement of its point 18 by projection *f* of device *d* under pressure by spring 16, and the pawl 5 comes into engagement at the same time by its spring 25. Then as the handle is depressed it will first lower the pawl 5 a sufficient distance before it is released to raise pawl 4 from domination by device *d* and to bring it into engaging relation with the tooth next above the one from which it was last released, and pawl 5 will be disengaged only when pawl 4 is ready to act. Then as this action is repeated the rack-bar will rest on pawl 4, and the lowering of said pawl by raising the handle will lower the rack-bar also one tooth to be engaged by pawl 5, and so on. The action is positive and unfailing, and since a vehicle is usually raised only far enough to clear a wheel from the floor the operation does not involve either much time or adjustment and a tooth-by-tooth operation suffices.

Referring now to Fig. 4, we have the same parts as in the foregoing figures but showing the pawl lifting unit *d* as retired and out of operation through the action of cam 15 and the rack-bar as adapted to be raised. Hence in this case the said device is not in position to act upon the pawls and both are in positive engaging relations with the rack-bar, one acting on the down stroke of the handle and the other on the up stroke. Both pivots 3 and 6 being relatively near the pivot 7 of the handle the operation in any case is comparatively easy and each pawl takes up and holds what has been raised by the other one.

Fig. 5 contains a modification in the location of the pawl 5. In this view the said pawl is pivoted in the wall 8 of the standard instead of being on the handle or handle socket *h*, and relatively above the said socket as shown. Hence to operate the same by or through the lift unit or device *d* I provide the said device with an upwardly projecting finger or extension 26 which is curved inwardly at the top to come beneath the toe or point 18 on said pawl behind the pivot 6 thereof, so that when pawl 5 is freed from engagement with the rack-bar it will be swung back out of engaging relations therewith by the upward movement of the device *d* after the manner and for the purpose set forth in connection with Figs. 1 and 2.

The modification in Fig. 6 shows the small or inner pawl 5 as pivoted on the extremity of the lever or handle socket and the outer and larger pawl pivoted on the handle pivot

7, and in order that said pawl 5 may be thrown out of engaging position upon the rack-bar the lower extremity or point of said pawl behind its pivot is curved or bent inwardly at 20, more or less as in the other views to bring the said extremity over the head 10 and off center with said pivot 7. This arrangement provides for the raising of the said head, the lift action of spring 16 which has the requisite strength to always actuate the pawls when free and to throw pawl 5 back away from teeth 2 when said pawl is liberated therefrom through the engaging action of pawl 4. Otherwise the operation is the same as in the above described forms of the invention as to raising and lowering the rack-bar.

The lift member or unit *d* arranged and adapted to operate as herein described is especially emphasized as of the essence of the present invention.

What I claim is:

1. A lift jack as described having a standard with an enlargement at one side and a well at the bottom of said enlargement, a rack-bar slidably mounted within said standard, a handle and a plurality of pawls pivotally mounted within said enlargement to operate said bar, and a single releasing member for both said pawls and a spring for said member confined within said well to press the same upward, and springs to press said pawls into engagement with said rack-bar.

2. A lift jack as described having a standard and a rack-bar therein, a set of pivotally supported pawls adapted to engage said bar, springs for said pawls, an operating handle with which said pawls are operatively related, a single releasing member for said pawls slidably mounted beneath the same and in said standard and provided at its top with stepped contact surfaces to separately engage and actuate said pawls, and a single spring to raise said releasing member having greater tension than said pawl springs.

3. A lift jack comprising a standard having a lateral enlargement at its top provided with a round well in its bottom and a rack-bar and handle in said standard, in combination with a pawl releasing device comprising a releasing member slidably mounted in said well and having a stem, a spring in said well to raise said member, a cam lever on said stem in bearing relation to the bottom of said well, a pair of spring pressed pivoted pawls adapted to engage said bar and having projecting portions opposite said member and adapted to be engaged thereby.

4. A lift jack as described comprising a standard having an enlargement with a barrel-shaped well perpendicularly in its bottom, a handle and a lift bar with rack teeth

in said standard, a pair of pivoted spring-pressed pawls adapted to engage said bar and having toe extremities, a single releasing member for the pawls in said well having a 5 stem slidably projected through the bottom of said well, upright and lateral projections on said member adapted to engage said toe extremities, a spring to raise said member, and means on said stem adapted to draw and

hold said member down out of engagement 10 with said pawls.

In testimony whereof I affix my signature in presence of two witnesses.

JOHN H. BURKHOLDER.
